WATERING DEVICE FOR POTTED PLANTS

John E. Goldring, Pebble Beach, Calif., assignor to
Agro International

Filed Mar. 8, 1972, Ser. No. 232,987

Term of patent 14 years

Int. Cl. D11—02

U.S. Cl. D35—3 A

FIG. 1

FIG. 2

FIG. 3

FIG. 4

FIG. 1 is a top plan view of a watering device for potted plants showing my new design.

FIG. 2 is a side elevational view thereof.

FIG. 3 is another side elevational view thereof.

FIG. 4 is a bottom plan view thereof.

I claim:

The ornamental design for a watering device for potted plants, substantially as shown.
